UNITED STATES PATENT OFFICE.

BRUNO ZABEL, OF FEURA BUSH, NEW YORK, ASSIGNOR TO TOSCA ZABEL, OF ELSMERE, NEW YORK.

LOOP-THE-LOOP TOY.

Application filed January 20, 1926. Serial No. 82,481.

This invention relates to mechanical toys, and particularly to the type commonly referred to as "loop-the-loop" toys, wherein an object is caused to roll by gravity along a track in which there is a vertical loop. In passing along the track, the object is caused to roll around the loop.

The invention relates more particularly to toys of the type wherein there is a track having an intermediate loop portion with oppositely inclined end portions which may be alternately raised, and has for its object to provide a simple mechanical construction for imparting the necessary rocking or tilting motion to the track.

In the present invention I have illustrated a form of loop-the-loop toy wherein the track contains two loops, this particular form of loop track being shown in my prior Patent No. 1,568,492, dated January 5, 1926, for a double loop-the-loop toy. However, the invention is not confined to the particular form of loop track shown in my said prior patent as any loop track having an intermediate loop portion and oppositely inclined ends may be utilized, the present invention pertaining merely to a means for supporting the loop track and providing a rocking support therefor.

The invention may be readily understood by reference to the accompanying drawings which illustrate a preferred embodiment of the invention but to the details of construction of which my invention is not confined.

In the drawings:—

Figure 1 represents a plan view of a toy embodying my invention;

Figure 2 is a side elevation thereof;

Figure 3 is a perspective view of the support or mounting for the loop track; and

Figure 4 represents a section on line IV—IV of Figure 2.

In the drawings, 2 designates a base member which is preferably formed from an integral piece of sheet metal, and which has a platform portion 3 and depending side portions 4 which have arcuately curved lower edges 5 so as to provide rockers. The curved lower edges are preferably curled to form a strengthening bead, as shown in the drawing.

Mounted on the base member 2 is the looped track designated generally as 6. In its preferred form it is comprised of two sections having loops 7, horizontal exten-

sions 8 and inclined extensions 9, the extensions 8 and 9 comprising the opposite terminals of the loop 7. The two horizontal portions 8 rest on the portion 3 of the base, and their ends are preferably brought together at 10. The platform 3 preferably has upturned ears 11 which pass through the portions 8 of the track to firmly secure the respective track members to the base.

The upper portions of the respective loops 7 are preferably connected and held rigid by means of a spreader or connector 12. The oppositely inclined extensions 9 are preferably provided with removable inclined track portions or extensions 9^b, these extensions having terminal portions 9^c which are normally substantially horizontal. At the extreme ends of each of these removable track sections is a stop 9^d.

Rigidly secured to the base member 2 is a suitable handle member 13 by means of which the base may be rocked.

In operation, a gravity propelled object such as the toy car 14 shown in Figure 2 is placed on one of the looped track terminals. The track is then rocked until the terminal on which the gravity propelled object is set is inclined sufficiently for the car to roll therefrom down the inclined track portion 9^b. In moving down the inclined portion 9^b the car gains sufficient acceleration to carry it around the first loop 7 along the horizontal track portions 8 and around the second loop 7. It will continue to roll from the second loop along the opposite track section 9^b which has by this time been rocked until it is in a substantial horizontal position.

When the car or gravity propelled object reaches the extremely opposite end of the track, the operator rocks the base 2 in the opposite direction inclining the whole track in the opposite direction from that of the first operation whereby the car is caused to travel along the tracks and around the loop 100 in the reverse direction to the starting terminal. By continuously rocking the base back and forth at the proper speed, the car may be caused to travel first in one direction and then in the other direction around the 105 looped track from one end thereof to the other.

Toys of the loop-the-loop, type as heretofore constructed, have always been of the motor operated type, a spring having been 110

employed for imparting the necessary tilting motion to the track. Where a spring motor is used, the expense of the toy is materially increased and it cannot be made as rugged as, or guaranteed to give the satisfaction of, a hand operated toy. Furthermore, extremely small children find difficulty in winding a spring operated toy, but such children would quickly learn to rock a hand operated device.

The present invention provides a simple form of mounting for the looped track which enables it to be easily operated by hand and which is extremely simple to manufacture and assemble and which is extremely cheap. At the same time the track is provided with a mounting by means of which a very smooth and steady movement can be imparted to the track, and this is desirable as any unevenness might be unsatisfactory as it would be likely to result in the gravity propelled object being derailed in one or the other of the loops. While I have illustrated the invention as being adapted to a track having two loops therein, it will be understood that it is applicable to a track having any number of loops operatively disposed along the track in such manner that a car can be caused to travel around them when the track is tilted in the manner herein described.

I claim as my invention:—

1. A mechanical toy including a looped track, a rocker on which the track is mount-

ed, and a gravity propelled object in the track.

2. A mechanical toy including a track with oppositely inclined sections and an intermediate loop, and a rocker on which the track is supported.

3. A mechanical toy including a track having a pair of spaced apart loops with a connecting portion between the loops and an incline leading up from each loop, and a rocker on which the connecting portion of track is set and to which it is secured.

4. A mechanical toy including a looped track member, a gravity propelled object adapted to roll along the track, and a rocker platform on which the track is carried.

5. A mechanical toy including a looped track member, a gravity propelled object adapted to roll along the track, a rocker platform on which the track is carried, and an operating handle on the platform.

6. A mechanical toy including a looped track, a platform on which the track is carried, a pair of rockers on the platform, and a gravity propelled object adapted to roll in the track.

7. A mechanical toy including an integral sheet-metal platform having downwardly turned rockers at each side thereof, a looped track on the platform, and a gravity propelled object in the track.

In testimony whereof I have hereunto set my hand.

BRUNO ZABEL.
